US00D558783S

(12) **United States Design Patent** (10) Patent No.: **US D558,783 S**
Andre et al. (45) Date of Patent: ** *Jan. 1, 2008

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Steve Jobs**, Palo Alto, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/257,234**

(22) Filed: **Mar. 31, 2006**

Related U.S. Application Data

(63) Continuation of application No. 29/220,038, filed on Dec. 23, 2004, now Pat. No. Des. 529,044, which is a continuation of application No. 29/220,035, filed on Dec. 23, 2004, now Pat. No. Des. 534,921.

CLAIM

We claim the ornamental design for a media device, substantially as shown and described.

DESCRIPTION

FIG. 1 is a perspective view of media device in accordance with the present design. The media device can, for example, be a media player or a media storage device, and more particularly a music player such as a flash-based MP3 player.

FIG. 2 is a front view for the media device.

FIG. 3 is a rear view for the media device.

FIG. 4 is a right side view for the media device.

FIG. 5 is a left side view for the media device.

FIG. 6 is a top view for the media device; and,

FIG. 7 is a bottom view for the media device.
